UNITED STATES PATENT OFFICE.

JESSE EMMERSON BURKILL AND WALLACE SUNDERLAND, OF MORLEY, ENGLAND.

MACHINE FOR MAKING CORES OR MOLDS.

SPECIFICATION forming part of Letters Patent No. 790,781, dated May 23, 1905.

Application filed September 16, 1903. Serial No. 173,422.

To all whom it may concern:

Be it known that we, JESSE EMMERSON BURKILL and WALLACE SUNDERLAND, subjects of the King of Great Britain and Ireland, whose postal address is The Yorkshire Engineering and Fuel Economiser Works, Bridge Street, Morley, in the county of York, England, have invented certain new and useful improvements entitled "A Machine for Making Cores or Molds," (for which application for a patent has been made in Great Britain, numbered 577, dated January 9, 1903,) of which the following is a specification.

15 Our invention relates to a machine for making cores or molds, and has for its object the construction of a machine for pressing cores or patterns by compressed air or hydraulic power in which the exhaust is used 20 for drawing or turning out the core. The machine may also be used as a molding-machine.

In describing our invention in detail reference is made to the accompanying sheets 25 of drawings, similar letters indicating similar parts, in which—

Figure 1 is a front elevation of our improved machine. Fig. 2 is a sectional elevation through line *a b* of Fig. 1. Fig. 3 is a 30 sectional elevation through line *c d* of Fig. 1. Fig. 4 is a side elevation. Fig. 5 is a sectional elevation of our machine as used as a molding-machine.

In carrying out our invention the admission of the water or air to operate the ram *A* 35 may be controlled by a suitable three-way cock or valve or valves *B*. The air or like cylinder *C*, in which said ram *A* works, and bed-plate *D* may be made in one piece. The 40 working stroke of the ram *A* is preferably upward, the sand or the like being filled into the recess *E* around the die *F*, which is removable, but can be firmly attached to the ram *A* by means of a bolt, as shown. On the 45 completion of the upward stroke of the ram *A* the catch or like *M*, attached in any convenient manner to the outer portion of the ram *A*, engages with the adjustable nut or like *N*, which is attached to lever *O* and

raises the weighted lever *P*, thereby opening 50 the valve *R*. Suitable movement of the valve *B* closes the admission-port and permits communication between the chamber *C'*, the exhaust-pipe *G*, and the flexible pipe *G'*. This allows a certain quantity of air or 55 the like to escape back through the pipe *B'* and through the pipe *G* and out through the escape-valve *R*, thus allowing the ram *A* to fall by reason of the weight of such ram overcoming the pressure in chamber *C'*. The 60 valve *R* is then automatically closed by the action of the weighted lever *P*, and the remaining air or the like is forced by the descending ram through pipe *B'* and pipe *G*, thence through flexible pipe *G'* to the annular space *H*, provided underneath the ring-tube or cylinder *J*, which forms an air-piston supporting the bottom of the core or cake. The air or like passing to the before-mentioned annular space *H* raises the air-piston 70 *J* until the finished core or the like is pushed or blown level with the top *K* of the main piston or cylinder, when the said core may be removed.

This machine is especially applicable for 75 making cores for castings of all kinds of pipes and round articles.

To use our machine as a molding-machine, the construction is as shown in section in Fig. 5. There is one cylinder *C'* and bed-plate *D'*, which may be made in one piece, as before. The ram *A'* is attached to what might be termed the "bottom plate" *A* of the molding-box, in which are the patterns *S*, supported on the upper part of said ram, 85 the sand being filled in in the ordinary way. The action of this ram is identically the same as before described. Instead of there being one cylinder *J* there are two such cylinders *J'*, actuated, as in the case of the core-machine, by means of flexible or like pipes attached to the exhaust-pipe *G*. On the compressed air or the like acting on the ram *A* the sand is compressed against the top plate *U'*. On the ram descending the exhaust-air 90 or the like pressure acts on the rams in cylinders *J J* and lifts the molding-box clear of the patterns. The molding-box can then be re-

moved as required. A stop T, working in groove V, is provided, as shown in Fig. 5, in order to prevent the ram A² from being blown out. Similar stops are also provided 5 on the smaller cylinders J'.

What we claim as our invention is—

1. The combination of a frame, a cylinder, a ram, a mold carried by one of the members comprised by the cylinder and ram, a piston 10 and cylinder for ejecting a body from said mold, with means for directing fluid into said second cylinder after it has been used in the first cylinder, substantially as described.
2. The combination of a frame, a cylinder, 15 a ram, a mold carried by one of the members comprised by the cylinder and ram, a die in said mold, means including a hand-operated device for controlling the flow of motive fluid to said cylinder, a second cylinder, a 20 piston therefor placed to eject bodies from the mold, and automatic means independent of said hand-operated means for causing said second cylinder to be supplied with motive fluid, substantially as described.
3. The combination of a frame, a cylinder, 25 a ram, a mold carried by one of the members comprised by the cylinder and ram, an auxiliary piston, a cylinder therefor, a die in the mold, said die being removable independently of said piston, and connections whereby motive fluid may be supplied to the first cylinder and then exhausted therefrom to the second cylinder for the actuation of said auxiliary piston, substantially as described.
4. The combination of a frame, a cylinder, 30 a ram, a mold carried by one of the members comprised by the cylinder and ram, a die in said mold, a second cylinder and an annular piston therefor placed to eject bodies from 35 said mold, with means for directing fluid exhausted from the cylinder so that it will act

upon said annular piston, substantially as described.

5. The combination of a frame, a cylinder, a ram, a mold carried by one of the members 45 comprised by the cylinder and ram, a piston for ejecting a body from said mold, a cylinder therefor, and a valve having connection whereby the first cylinder may be supplied with motive fluid, or the first cylinder connected with the second cylinder at will, substantially as described.

6. The combination of a frame, a cylinder, a ram, a mold carried by one of said members, an auxiliary cylinder, a ram therefor placed 55 to eject bodies from the mold, a main valve having connections to both of said cylinders and to the source of supply for motive fluid, with an auxiliary valve connected to the auxiliary cylinder, and means for automatically 60 operating said auxiliary valve, substantially as described.

7. The combination of a frame, a cylinder, a ram, a mold carried by one of said members, an auxiliary cylinder, a ram therefor placed 65 to eject bodies from the mold, a main valve having connections to both of said cylinders and to the source of supply for motive fluid, with an auxiliary valve in connection to the auxiliary cylinder, means for normally retaining said auxiliary valve in a closed position, and an arm carried by the mold-supporting structure for opening said auxiliary valve, substantially as described.

In witness whereof we have hereunto set 75 our hands in the presence of two witnesses.

JESSE EMMERSON BURKILL.
WALLACE SUNDERLAND.
